UNITED STATES PATENT OFFICE

WILLIAM E. COOK, OF ST. GEORGE, NEW YORK, ASSIGNOR TO GENERAL CABLE CORPORATION, OF NEW YORK, N. Y., A CORPORATION OF NEW JERSEY

STRANDED WIRE CONNECTER

Application filed May 16, 1929. Serial No. 363,607.

My invention relates to stranded wire connectors, and more particularly to a device of this kind for use with electrical conductors, and particularly stranded wires.

Connecters of the type to which my invention relates are designed for use with conductor wires, the size of which is such as to preclude the bending of the wire when connecting different lengths of same. Great difficulty has always been experienced by linemen when splicing such heavy wires, and the operation has always required a considerable length of time and interferred with the work of a gang of linemen while such splices were being made. In addition to the loss of time, there was always a possibility, by reason of the conditions under which such work is done, of the presence of mechanical weakness in the splice, and a condition increasing electrical resistance of the conductor at the splice.

The splicing of adjacent lengths of stranded wires has always been a source of great trouble, since it required the untwisting of the different strands of the cable, the cleaning of each strand and the formation of a splice as to each strand.

So far as I know, no devices for mechanically and electrically connecting lengths of heavy stranded conductor cables, which could be quickly connected to the cables by hand, have heretofore been used.

With the above conditions in mind, I have provided a connector which is so constructed as to permit the hand insertion of the ends of different lengths of stranded cables therein, and firmly grip and compress the various strands of the cable in a manner to prevent the removal of the cable from the connector while forming a proper electrical connection between the cable and the splicer.

The connector of my invention embodies a plurality of sets of closing jaws mounted within a casing or shell, having an open end adjacent each set of said jaws, said shell and said jaws having co-operating wedge surfaces toward the open end of the shell through which the cable is inserted, so that stresses longitudinally of the cable will tend to increase the gripping action of the jaws upon the cable. The jaws and the shell therefor,

in addition to possessing sufficient inherent strength to resist distortion as a result of stresses thereon by the cable, are so constructed as to possess electrical conductivity equal to, or greater than, that of the cable, which result is secured by proper dimensions of, and material in, the shell, and the necessary intimate connection between the jaws and the shell and between the jaws and the cable.

Certain tolerance is always allowed in the diameter of conductor wires and cables, so that in constructing a connector having sliding jaws of the character above referred to, provision must be made to secure a substantially uniform contact area between the jaws and the shell, irrespective of allowable variations in the diameters of different wires or cables.

Tests have shown that with a connector embodying my invention, strains upon the wire sufficient to break same may be developed without any impairment of the joint made by the connector. Such tests with stranded cables have shown that all of the strands, including the center strand, will break. Such breaking of the wire or cable, however, has always occurred closely adjacent the point of contact between the end of the jaws and the wire or cable, possibly due to the bite of the jaws upon the wire or cable at this point, although during tests it has been shown that such breaking of the wire or cable does not occur under stresses below the normal breaking point of such wires or cables.

I have found it preferable, however, to so construct the jaws as to secure a graduated gripping action progressively increasing inwardly of the end opening of the shell. In this manner I secure the desired surface contact between the wire or cable, the jaws and the shell, but avoid possible weakening of the wire as a result of the cutting action of the jaws necessary to secure a firm grip upon the wire or cable and an adequate surface area contact.

In a connector embodying therein sliding wedge-shaped jaws, it is obvious that with the movement of the jaws along the co-operating wedge-shaped walls of the shell when

the jaws open to receive a wire or cable there will be a separation thereof, one from the other, and that when such connectors are used with stranded wires or cables, the outer strands will almost invariably spread and enter the space between the jaws, thus preventing a proper closing thereof upon the cable.

To avoid this condition, I provide a cupped closure shield engaged by the jaws and adapted to receive and confine the loose ends of the strands of a stranded wire or cable, so that during the movement of the wire or cable inwardly of the shell with the jaws, the latter may have the desired opening movement to permit the passage of the wire or cable and the shield and thus ensure the proper closing action of the jaws directly upon the cable.

This shield will also serve when the connector is not in use to exclude dirt from within the shell and the jaws, and in large measure prevent oxidation of the gripping teeth of the jaws, which might result in the development of resistance in the connector.

I also provide, in a connector embodying the invention, means automatically closing the jaws upon the wire or cable upon the completion of the movement thereof when inserting same within the connector, and means limiting the extent of penetration of the end of a wire or cable within the shell.

The invention consists primarily in a stranded wire connector embodying therein a shell, open at both ends and interiorly tapered in opposite directions toward its open ends, a set of exteriorly tapered gripping jaws adjacent each end of said shell, springs acting to normally thrust said jaws toward the adjacent open end of the shell, and cupped shields substantially closing the openings in said shell and engageable by the jaws; and in such other novel features of construction and combination of parts, as are hereinafter set forth and described, and more particularly pointed out in the claims hereto appended.

Referring to the drawings,

Fig. 1 is a longitudinal section through a connector embodying the invention, the cupped shield at one end of the shell being shown in a position exteriorly of the shell to permit a showing of the formation of the outer portion of the jaw;

Fig. 2 is a similar view with the ends of adjacent lengths of cable in position in the connector;

Fig. 3 is a fragmentary portion of one end of the connector in section, upon an enlarged scale, preparatory to the insertion of a wire end therein;

Fig. 4 is a similar view with the end of the wire in position within the connector;

Fig. 5 is a transverse section showing the conditions with a stranded wire of exact diameter;

Fig. 6 is a similar view with a slightly over-sized wire;

Fig. 7 is a view similar to 5 and 6 with a slightly undersized wire; and

Fig. 8 is a view of one of the gripping jaws.

Like letters refer to like parts throughout the several views.

In the embodiment of the invention shown in the drawings, the connector is composed of a shell made in two parts *a* and *b* having a screw threaded connection as shown at *c* to facilitate the assembly of the connector. Held in position by the screw threaded connection *c* is a stop diaphragm *d*, forming a spring seat in a manner to be hereinafter described, and limiting the extent of penetration of the wire within the shell, as shown more particularly in Figs. 2 and 4.

The shell *a*—*b* has an opening at each end thereof at *a'* and *b'* respectively, and the opposite ends of this shell are reversely tapered at *a''* and *b''* toward the openings *a'* and *b'* respectively. The tapered portions of the shell are substantially cylindrical in cross section, as shown in Figs. 5 to 7. The exterior of the shell may take any desired form, that illustrated being merely for the purpose of conserving material in the production of the shell and permitting the connector to be drawn freely over cross arms of the poles carrying the wires.

The shell *a*—*b* is made of highly electro-conductive material, and is of a thickness to not only provide a cross sectional area equal to, or greater than, that of any wire with which the connector may be used, but to afford sufficient strength therein to resist expansion thereof adjacent the openings *a'* and *b'* as a result of the heavy stresses to which connectors of this type are subjected, which may amount to three or four tons, or even more with exceptionally heavy wires or cables.

Slidably mounted within, and adjacent each end of, the shell *a*—*b* is a set of gripping jaws, each consisting of the segment of a truncated cone having a cylindrical gripping face provided with suitable teeth or gripping areas capable of penetrating the copper conductor wires with which the connector is used, to only a limited extent however.

In the accompanying drawings, each set of such jaws is shown as consisting of three segments *e*, *f* and *g* which, when closed together as stated, form a truncated cone, the outer wedge-like surface *e'*—*f'*—*g'* of which are adapted to slide along and engage the interior wedge-like surface *a''* or *b''* of the shell. It is obvious that with the movement of these jaws, the gradually increasing diameter of the opening within the shell will permit them to separate so as to increase the diameter of the opening within the jaws to permit the passage of a wire, the diameter of which is

relatively greater than the diameter of the toothed opening within the set of jaws. The teeth of the jaw elements *e*, *f* and *g* are shown at *h*.

5 Acting between the disk *d* and the inner ends of each set of jaws is an expansion spring *i*.

Since the jaw construction at one side of the disk *d* is identical with that at the other 10 side, the same reference letters are used in connection with the jaws and with the spring at one side of said disk, as are used with the corresponding parts on the other side thereof.

The detailed construction of the jaws for 15 securing a progressive increase in their effective gripping action, inwardly of the opening *a'* or *b'*, and for causing them to adapt themselves to wires of varying diameters, will be more fully described hereinafter.

20 It is obvious that with the movement of the jaws of one set inwardly of the shell, they will move circumferentially away from each other as the wire is inserted between the jaws. This spacing of the jaws, when they are 25 opened, is shown at *x* in Figs. 1, 3, 5 and 6 of the drawings, and will vary with different degrees of movement of the jaws inwardly of the shell.

Since the strands at the end of the wire or 30 cable are unconfined, it is obvious that such ends are free to spring outwardly and enter the spaces *x*, thus preventing the subsequent closing of the jaws by a reverse movement thereof, initially by the spring *i*, and subsequently by the pull upon the cable or wire.

To correct this condition, I provide a 35 cupped shield *j*, preferably made of thin, soft metal such as copper, which may be positioned within the open ends *a'* or *b'* of the shell and be engaged by the jaws adjacent each said open end. The lip *j'* of said shield is flared outwardly so as to substantially engage the shell and preferably is of greater diameter than the mouth of said opening.

40 This shield has three distinct functions. The first is to confine the separate strands of the wire when it is inserted in the jaw, and prevent the spreading of the strands during the insertion of the wire in the connector, 45 and subsequently thereto. The second function is to exclude dirt and other foreign matter from the shell when the connector is not in use, and substantially exclude atmospheric air therefrom so as to minimize possibility 50 of oxidation of the teeth *h*. The third function is to prevent a lineman from thrusting his finger within the connector which would result in the necessity for taking down the connector in order to release the finger without injury thereto.

The material of said shield is such that when it is forced inwardly between the jaws, the flared lip thereof will readily deform so 55 as to pass the jaws, and yet the shield must possess sufficient strength to resist the crush-

ing strains developed by the spring *i*, said spring being a fairly stiff spring.

To prevent the maximum bite of the jaws upon the wire or cable occurring closely adjacent the opening *a'* or *b'*, the outer wedge-like surfaces *e'*, *f'* and *g'* are given a higher pitch than the tapered portion *a²* or *b²* of the shell, the variation however being measured only by a few thousandths of an inch. As a consequence of this construction, the jaws *e*, 70 *f* and *g* will initially close upon the wire or cable adjacent the spring *i*, there being a progressively decreasing penetration of the teeth *h* toward the opening *a'* or *b'*, although all of the teeth will firmly grip and penetrate 75 the wire or cable.

In Fig. 1 of the drawings, to the right I have shown this condition greatly exaggerated, the shield *j* being shown separated from the shell at this side for the purpose of illustrating this condition.

There is a further condition, due to the tolerance allowed in conductor wires or cables, which has to do with matter of the conductivity of the connector. The tapered portions *a²* and *b²* of the shell have the same pitch throughout, and it is obvious will vary in diameter at every point thereof. The segmental gripper jaws *e*, *f* and *g*, when brought together being in substantially the form of a 90 truncated cone, can conform to and bear against the tapered portions *a²* or *b²* only in one position of the jaws. If these jaws, when they close upon the wire, are inwardly of the shell as to this position, it is obvious that 95 where they engage the tapered portion, the opposite edges of each segment will be spaced away from the shell, and if, when they grip the wire or cable, they be away from this position toward the opening *a'* or *b'*, it is 100 105 obvious that the point of engagement of the jaws with the shell will be only along adjacent edges of the segment.

Expressed in another way, as the jaws separate they lose their true conical form, and the radius of the arc of the wedged outer surface thereof will be of a radius relatively shorter than the radius of the tapered portion of the shell. Consequently, the arc of each 110 segment bears the relation to the tapered portions, of a small circle within a larger circle.

The same condition will be present if the jaws are beyond their normal engaging point toward the opening *a'* or *b'* except that then the engaging portion of the jaws will be of a longer radius than the adjacent portion of the tapered opening within the shell. Under either condition the result is a reduction in that contact area between the jaws and the shell necessary to the degree of conductivity 115 120 required to avoid the development of resistance in the connector.

To correct the above conditions, I provide each jaw segment *e*, *f* and *g* with one or more 125 longitudinally extending weakened portions 130

- k* throughout the length of each jaw segment. These portions *k* are in the form of slots extending well into the body of the jaws, and their presence will cause the deformation of a segment as a result of the pull thereon in stretching a wire, or while the wire is in position, so as to cause substantially every portion thereof to conform in radius to the portion of the interior taper of the shell with which it contacts. This will cause the jaws to automatically adapt themselves to wires of different diameters, as to the gripping jaws, and to adapt themselves to the portion of the shell with which they engage, so as to secure the maximum electrical contact at all times, irrespective of variance in the diameter of different wires or cables.

The operation of the herein described connector is substantially as follows:-

- 1.0 The herein described connector is for use with electrical conductor wires or cables, and is adapted to be permanently incorporated in a line of such wires or cables being stretched by the linemen.
- 23 The parts *a* and *b* of the shell are made separate and connected in the manner described merely to facilitate the assembly of the connector, and preferably the joint between the two sections will be permanently connected by soldering before the connector goes into use. This is to prevent any possible breakage of the line, due to the loosening of the screw threaded joint *c* as a result of movement of the line from vibration due to wind or other conditions.

43 The stop disk *d* is held in position by the abutting edges of the two portions *a* and *b* of the shell, and the springs *i* are tensioned as a result of the connection of the two shell portions so as to have a normal tendency to thrust the jaws *e*, *f* and *g* toward the open ends *a'*—*b'* of the shell. These springs are of a diameter relatively greater than the toothed opening of the jaws, so as to permit the free passage of the wire or cable through the springs until the end thereof is in abutting relation with the stop disk *d*, (see Fig. 2).

50 Before the jaws, the springs and the disk are properly assembled within the shell, cupped shields *j* are placed within the open ends *a'*—*b'* of the shell, thus holding the jaws inwardly of the shell, the tension of the spring *i* causing the opening within the jaws to be enlarged to an extent to receive and engage said shield. The exterior diameter of said shield is relatively greater than that of the wire or cable with which the connector is to be used. The shield is positioned within the shell with the lip *j'* thereof projecting over the ends of the jaws into substantial contact, circumferentially of the lip, with the shell. As heretofore stated, the positioning of this shield within the opening, and its retention therein by the jaws will close the openings

a' and *b'* and protect the jaws while the connector is not in use.

When it is desired to make a splice, it is merely necessary for the linemen to take the end of the stranded wire or cable and locate it within the cupped shield *j*, the flared lip of which will guide all of the outer strands to within the cup. This can be instantly done, and by a continuing pressure the cup and the confined end of the wire or cable may be forced inwardly of the shell. The sides of the shield effectively prevent any of the outer strands of the wire or cable springing outwardly in the gap between the jaw segments *e*, *f* and *g*. Furthermore, the shield ensures a simultaneous, similar opening movement of each of the jaws which might not be the case if the wire or cable had an irregularly cut end.

85 Springs *i* will be further tensioned as a result of the movement of the jaws of a set inwardly of the shell, but immediately upon the shield passing the inner ends of the jaws, said springs will act to close the jaws upon the wire or cable adjacent the portion thereof confined by the shield.

90 The mounting of the end of the wire in the connector requires merely a second or two, and the shield, still upon the wire, will contact with the stop disk *d* substantially simultaneously with the closing of the jaws upon the wire or cable.

95 When the wire is once positioned and the jaws closed upon same, a pull upon the wire incidental to the stretching of the wire between poles, or the subsequent sag of the wire, will merely increase the effective grip of the jaws upon the wire until the teeth *h* thereof have penetrated the wires to the maximum extent. These teeth may be ordinary screw threads, or may be ratchet teeth, as desired, the teeth being very short and numerous to prevent excessive cutting of the wire while ensuring a contact area equal to, or greater than would be secured by a plain 100 jaw.

105 Owing to the necessity of the avoidance of likelihood of loose ends of wire, due to the failure of a connector, gripping teeth upon the jaws are essential.

110 If the wire or cable be of standard diameter, the jaws will ultimately position themselves so that the outer surface thereof will be throughout its extent, substantially coincident with the surface of the tapered portions *a*² and *b*². The variance in the pitch of the wedge-shaped exterior surfaces of the jaw segments, as compared with that of the tapered portions *a*²—*b*², will have the effect of merely limiting the extent of penetration of the teeth *h* at the end of the jaw adjacent the open end *a'* or *b'* of the shell. As stated, this variance is merely a few thousandths of an inch, and is compensated for by the increased penetration of the teeth towards the 115

inner ends of the jaws, so as to secure electrical contact between each jaw and the shell for the full length and width of the jaw. This condition ensures the strongest bite of the jaws well within the shell, and a progressively lighter bite of the teeth of the jaws toward the open end of the shell, and serves to prevent the stresses resulting from pull upon the wire being applied directly to a portion of the wire, where the maximum penetration of the teeth *h* occurs.

With a wire of standard diameter, and by standard is meant the exact diameter called for without taking advantage of the tolerance allowed, the jaws will be positioned in the shell where every portion of the exterior thereof will be forced into intimate contact with the shell. If a wire or cable, however, be of a diameter above standard and yet within the tolerance allowed, a solid segmental jaw would contact with the shell only along the high point of the arc of the outer surface of the jaw were it not for the weakened portions *k* which will permit the expansion of the jaw at both sides of the point of contact, as a result of the closing of the weakened portions *k*, as shown in Fig. 6, or of the breakage of the jaw adjacent the bottom of said weakened portion. Either condition will suffice to change the diameter both exteriorly and interiorly of the jaw so as to permit it to conform to the shell, and also to the wire or cable.

If the wire or cable be undersized and yet within the tolerance allowed, the jaw, if solid, would engage the shell only adjacent opposite edges of the segment. The weakened portions *k*, however, will permit the collapsing of the jaw intermediate the sides of the segment, thus reducing its diameter as a whole, both exteriorly and interiorly of the jaw, with the same result in securing electrical contact between the shell and the jaw, and the jaw and the wire, as heretofore referred to in connection with Fig. 6. This condition is shown in Fig. 7. The condition with the standard size of wire is shown in Fig. 5.

It will be noted, by reference to Figs. 2 and 4, that the shield *j* remains upon the end of the wire or cable, but has no further function after passing from the range of the jaws *e-f-g*, beyond preventing the spreading of the strands of the wire.

The action of the jaws *e, f* and *g*, in addition to gripping the wire in the manner described, is to firmly compact the different strands and thus ensure the desired electrical contact between these strands. The extent of this compaction is so great that in a testing machine, the center strand itself, which receives no mechanical support from any of the other strands, was held so firmly as to break at substantially the same time as the other strands.

A connector embodying the invention has been thoroughly tested by approved laboratories, not only as to its efficacy in forming an electrical joint between different lengths of wires or cables, but as to its holding capacity in making the connection.

Such tests have shown that the electrical resistance at the connector is substantially the same as in a section of the wire tested of substantially the length of the connector, and in fact, it was found that the connector did not develop as much heat as did the wire itself. As to the strength of the mechanical connection between the connector and the wire, the wire itself invariably broke without any yielding of the connection between same and the connector. The stresses to which such wires were subjected, at all times exceeded the requirement for tensile strength in the wire or cable.

The connector of my invention may be used with bare wires or cables, or with insulated wires or cables, it being necessary of course with the latter to strip the insulation therefrom before making the connection.

To ensure clean metal at the connection, between the jaws and the wire or cable, the lineman may turn the connector upon the wire which will serve to effectively remove from the teeth or from the wire or cable, any oxide or other foreign substance.

As heretofore stated, the exterior form of the connector is merely to facilitate the drawing of the wire or cable over cross arms when the linemen are stretching same.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A stranded wire connector embodying therein a shell, open at both ends and interiorly tapered in opposite directions toward its open ends, a set of exteriorly tapered gripping jaws adjacent each end of said shell, means acting to normally thrust said jaws toward the adjacent open end of the shell, and cupped shields substantially closing the openings in said shell and engageable by the jaws.

2. A stranded wire connector embodying therein a shell, open at both ends and interiorly tapered in opposite directions toward its open ends, a set of exteriorly tapered gripping jaws adjacent each end of said shell, means acting to normally thrust said jaws toward the adjacent open end of the shell, and cupped shields each having an outwardly flared lip, the bottom of said shields closing the space within said jaws and said outwardly flared lips substantially closing

the openings in said shell and the sides of said shields being engageable by the jaws.

3. A stranded wire connecter embodying therein a shell, open at both ends and interiorly tapered in opposite directions toward its open ends, a set of exteriorly tapered gripping jaws adjacent each end of said shell, the taper of said jaws being of a relatively higher pitch than the taper within said shell, means acting to normally thrust said jaws toward the adjacent open end of the shell, and cupped shields substantially closing the openings in said shell and engageable by the jaws.

4. A stranded wire connecter embodying therein a shell, open at both ends and interiorly tapered in opposite directions toward its open ends, a set of exteriorly tapered gripping jaws adjacent each end of said shell, the taper of said jaws being of a relatively higher pitch than the taper within said shell, means acting to normally thrust said jaws toward the adjacent open end of the shell, and cupped shields each having an outwardly flared lip, the bottom of said shields closing the space within said jaws and said outwardly flared lips substantially closing the openings in said shell and the sides of the shell being engageable by the jaws.

5. A stranded wire connecter embodying therein a shell, open at both ends and interiorly tapered in opposite directions toward its open ends, a set of exteriorly tapered circumferentially expandable and contractible gripping jaws adjacent each end of said shell, means acting to normally thrust said jaws toward the adjacent open end of the shell, and cupped shields substantially closing the openings in said shell and engageable by the jaws.

6. A stranded wire connecter embodying therein a shell, open at both ends and interiorly tapered in opposite directions toward its open ends, a set of exteriorly tapered segmental gripping jaws adjacent each end of said shell, each of said jaws having a weakened outer portion extending longitudinally thereof, means acting to normally thrust said jaws toward the adjacent open end of the shell, and cupped shields each having an outwardly flared lip, the bottom of said shields closing the space within said jaws and said outwardly flared lips substantially closing the openings in said shell and the sides of said shields being engageable by the jaws.

7. A stranded wire connecter embodying therein a shell open at both ends and interiorly tapered in opposite directions toward its open ends, a stop diaphragm within said shell, a set of exteriorly tapered gripping jaws adjacent each end of said shell, springs acting between said stop diaphragm and the jaws of each set to normally thrust said jaws toward the adjacent open end of the shell, and cupped shields substantially closing the

openings in said shell and engageable by the jaws.

8. A stranded wire connecter embodying therein a shell open at both ends and interiorly tapered in opposite directions toward its open ends, a stop diaphragm within said shell, a set of exteriorly tapered segmental gripping jaws adjacent each end of said shell, each of said jaws having a weakened outer portion extending longitudinally thereof, springs acting between said stop diaphragm and the jaws of each set to normally thrust said jaws toward the adjacent open end of said shell, and cupped shields each having an outwardly flared lip, the bottom of said shields closing the space within said jaws and said outwardly flared lips substantially closing the openings in said shell and the sides of the shell being engageable by the jaws.

9. A stranded wire connecter embodying therein a shell open at one end and interiorly tapered toward its open end, a set of exteriorly tapered gripping jaws adjacent the open end of said shell, means acting to normally thrust said jaws toward the open end of the shell, and a cupped shield substantially closing the opening in said shell and engageable by the jaws.

10. A stranded wire connecter embodying therein a shell open at one end and interiorly tapered toward its open end, a set of exteriorly tapered gripping jaws adjacent the open end of said shell, means acting to normally thrust said jaws toward the open end of the shell, and a cupped shield having an outwardly flared lip, the bottom of said shield closing the space within said jaws, and said outwardly flared lip substantially closing the opening in said shell, the sides of said shield being engageable by the jaws.

In witness whereof I have hereunto affixed my signature this 15th day of May, 1929,

WILLIAM E. COOK.
